Primary Examiner — Nathan M Johnston(57) **CLAIM**

The ornamental design for a liquid soap dispenser with holder, as shown and described.

DESCRIPTION

2. Liquid soap dispenser with holder

- 2.1 : Perspective
- 2.2 : Left
- 2.3 : Right
- 2.4 : Front
- 2.5 : Top

A dispenser for liquids comprising a lower pump body, an upper dispensing body connected thereto via a rod, and an angled holder that is located below the pump body; the bottle below the holder form no part of the claimed design; in design No. 2, the central part of the top of the dispensing body is also disclaimed.
